United States Patent Office

Des. 175,857
Patented Oct. 18, 1955

175,857

VACUUM CLEANER

Harold S. Ryden, Anaheim, Calif., assignor to Interstate
Precision Products Corporation, Anaheim, Calif., a cor-
poration of California

Application March 7, 1955, Serial No. 34,907

Term of patent 14 years

(Cl. D9—2)

FIG. 1.

FIG. 2.

FIG. 3.

FIG. 4.

FIG. 5.

Fig. 1 is a top plan view of the vacuum cleaner embodying my new design;

Fig. 2 is a view in side elevation of the same;

Fig. 3 is a bottom plan view of the same;

Fig. 4 is a front view in elevation of the same; and

Fig. 5 is a rear view in elevation of the same.

I claim:

The ornamental design for a vacuum cleaner, as shown.
